UNITED STATES PATENT OFFICE.

JOHN K. ROGERS, OF BROOKLINE, MASSACHUSETTS.

DESIGN FOR FONT OF PRINTING-TYPES.

Specification forming part of Design No. **11,484**, dated November 4, 1879; application filed August 15, 1879.
[Term of patent 3½ years.]

To all whom it may concern:

Be it known that I, JOHN K. ROGERS, of the town of Brookline, county of Norfolk, and State of Massachusetts, have invented and produced a new and original Design for a Font of Printing-Types, of which the following is a specification, the nature of the design being clearly shown in the accompanying typographic impressions, to which reference is made.

My design consists of an alphabet of capital letters, with figures, points, "short and," and dollar-mark, condensed and unshaded, each character showing a fine line above and a heavy or shade line below.

It further consists of a right (8) and left (1) ribbon end of three shaded waves and an intermediate ribbon-piece, 5, with two shaded waves, all with top and bottom lines, corresponding to the top and bottom lines of the letters, figures, &c., so that when used in connection therewith a ribbon of the thickness of the bottom line can be represented with words inscribed upon it.

It still further consists of a right (3) and left (2) end piece, top, bottom, and end line, connected by curved corner-lines, (concavo,) each embellished with a representation of a screw-head; also, an intermediate piece, 7, similarly constructed and embellished, and a screw-head alone, 6, with the top and bottom lines; and, again, a blank, with the same top and bottom lines, in each case the said lines corresponding with the lines on the letters, figures, &c., so that when used in connection therewith a tablet of the thickness of the bottom line can be represented with words inscribed upon it.

What I claim as new is—

The design for a font of printing-types, as described and shown.

JOHN K. ROGERS.
